UNITED STATES PATENT OFFICE.

CORNELIUS D. STOMLER, OF MARINE CITY, MICHIGAN.

SANITARY TOILET.

1,116,753.

Specification of Letters Patent. Patented Nov. 10, 1914.

Application filed September 2, 1914. Serial No. 859,793.

To all whom it may concern:

Be it known that I, CORNELIUS D. STOMLER, residing at Marine City, in the county of St. Clair and State of Michigan, have 5 invented certain new and useful Improvements in Sanitary Toilets, of which the following is a specification.

My invention, which relates to that class of sanitary toilets having means for feeding 10 a disinfectant into the bowl while flushing said bowl, primarily has for its purpose to provide a disinfecting attachment of a simple and economical construction, that can be readily applied to any of the ordinary 15 types of closet flushing mechanisms, without materially altering the said flushing mechanisms and without much expense.

My invention also has for its purpose to provide a disinfecting attachment for toilets adapted for connection with the conventional forms of flushing tank and pipe in which the disinfecting feed controlling valve is attached directly to the trip handle of the closet flushing valve and is also located with respect to the disinfectant holder and the water flow pipe to permit the first 25 part of the flushing water to enter the toilet bowl before the disinfectant discharges into and mixes with the water circulating 30 within the said bowl; and the said attachment also includes means for holding back the charge of disinfectant that passes through the feed controlling valve until the water flushing charge about completes its 35 course and comes to rest within the toilet bowl, the said disinfectant charge remaining with the water at rest within the bowl until the next flushing.

With other objects in view that will hereinafter appear, my invention embodies those peculiar features of construction and novel arrangement of the parts hereinafter fully explained, specifically pointed out in the appended claims and illustrated in the accompanying drawings, in which:

Figure 1 is a side view of the conventional type of toilet and flushing means therefor with my invention applied. Fig. 2 is a front elevation of the parts shown in Fig. 50 1. Fig. 3 is a longitudinal section that illustrates the connection of the disinfectant

outflow pipe with the flushing pipe. Fig. 4 is a side elevation that illustrates my improved disinfectant attachment with parts separated. Fig. 5 is a cross section of the 55 adjustable air vent device for the pipe connection for the disinfectant feed pipe.

In the drawings, 1 designates the toilet bowl, 2, the flushing tank, 3, the flow pipe from the tank to the bowl, and 4, the trip 60 handle that controls the flush tank valve.

My improved disinfecting attachment comprises a tank 5, preferably mounted upon one side of the flush tank 2, as shown 65 in Fig. 1.

6 designates the outflow pipe from the tank 5, which extends down to near the bottom of the flush tank 2 and laterally to connect with the disinfectant feed controlling valve 7 located directly under the tripper for the flush tank valve, the stem of which, in the construction shown, extends down through the tripper casing 8 and forms the stem 9 for the valve 7, such arrangement being provided so that the flush tank valve 75 and the disinfectant feed controlling valve are simultaneously opened when the tripper is pressed down to flush the closet.

10 designates the disinfectant flow pipe that connects with the trip or controlling 80 valve 7 and the said pipe enters the flushing pipe 3 near the outlet end thereof, as best shown in Fig. 3 of the drawings, by reference to which it will be noticed the end of the said pipe 10 terminates in an L-shaped nozzle 11 that points in the direction of the outflow of the flushing water and is provided with a back check 85 or ball valve 12, the purpose of which will presently appear and at a suitable point between the nozzle and the trip valve 7, the said pipe 10 is provided with an adjustable vent valve 13. By reason of connecting the valve that controls the flow of the disinfectant to the flushing valve 95 tripper, as shown, the operation of feeding a charge of disinfectant into the pipe 10, which enters the flushing pipe 3, is positively effected each time the closet is flushed and by pointing the nozzle end of the said 100 pipe 10 in the direction stated and providing it with a check valve, as shown and de-

scribed, it follows that when the toilet is flushed the water passing through the flushing pipe 3, creates a back pressure in the pipe 10 and thereby closes the valve 12 and holds the disinfecting charge, that passes into the said pipe 10 when the flushing valve was tripped, until the last portion of the flushing water passes through the pipe 3 and the said last portion of the water flow creates a suction that opens the valve 12 and thereby allows the disinfectant charge to now flow out and mix with the water still in circulation through the top part and sides of the bowl until it comes to rest with the remaining water in the bowl, there to remain until the next flushing, it being understood that the said flushing operations may occur as frequently as the tripper is pressed down and a disinfectant charge is at the same time obtained so long as the supply tank has disinfecting fluid therein.

By providing the disinfectant discharging pipe 10 with an adjustable air vent valve, as shown, the flow of the charge of the disinfectant within the said pipe is governed by the adjustment of the said vent valve.

Another and important advantage of my invention is that the same can be readily applied to the ordinary types of toilets and flushing tanks therefor without materially changing the flushing means, and at a comparatively small cost.

From the foregoing taken in connection with the accompanying drawings, the complete arrangement, and the manner of operating my invention will be readily understood by those skilled in the art to which it appertains.

40 What I claim is:

1. In combination with the flushing tank, the bowl, the flushing pipe and the flushing tank valve tripper; of a disinfectant holder, a pipe connection between the said holder and the flushing pipe to the bowl, a valve located in the said pipe connection operatively connected with the flushing tank valve tripper to be actuated as the tank valve is opened, and means controlled by the inflow of the flushing water for holding back the disinfectant charge until a part of the said flushing water has entered the bowl.

55 2. In combination with the flushing tank, the bowl, the flushing pipe and the flushing tank valve tripper; of a disinfectant holder, a pipe connection between the said holder and the flushing pipe to the bowl, a valve located in the said pipe connection operatively connected with the flushing tank valve tripper to be actuated as the tank valve is opened, means controlled by the inflow of the flushing water for holding back the disinfectant charge until a part of the said flushing water has entered the bowl,

and an adjustable air vent valve located in 65 the said pipe connection between its controlling valve and its discharging end.

3. An improvement for toilets of the character stated; comprising a disinfectant holder, a pipe connection between the holder and the flushing pipe, the said connection including a discharging nozzle located within the flushing pipe and pointed in the direction of the outflow through the said flushing pipe, a back check valve located in the 70 end of the pipe connection, a disinfectant charge controlling valve in the said pipe connection adapted for being operatively connected with the tripper device for the flushing tank valve and to be opened when 75 the said tripper device is actuated to open the flushing tank valve.

4. An improvement for toilets of the character stated; comprising a disinfectant holder, a pipe connection between the holder and the flushing pipe, the said connection including a discharging nozzle located within the flushing pipe and pointed in the direction of the outflow through the said flushing pipe, a back check valve located in 80 the said end of the pipe connection, a disinfectant charge controlling valve in the said pipe connection adapted for being operatively connected with the tripper device for the flushing tank valve and to be opened 85 when the said tripper device is actuated to open the flushing tank valve, and an adjustable air vent located in the pipe connection 90 that leads the disinfectant into the flushing pipe.

5. In combination with the flush tank, the bowl, the water flow pipe between the tank and the bowl and the tank valve tripper; of a disinfectant tank, a pipe connection between the said disinfectant tank and the said water flush pipe, and a valve located in the said pipe connection having a stem positioned to be directly operatively engaged by the said tripper.

6. In combination with the flush tank, the bowl, the water flow pipe between the tank and the bowl and the tank valve tripper; of a disinfectant tank, a pipe connection between the said disinfectant tank and the said water flush pipe, a valve located in the 110 said pipe connection having a stem positioned to be directly operatively engaged by the said tripper, the said pipe connection between the said disinfectant tank and the said flushing pipe being of relatively greater 115 length than the length of the said flushing pipe whereby the water will commence to enter the bowl before the disinfectant enters and mixes therewith.

7. In a sanitary toilet, the combination 125 of the bowl, the flushing tank, the flow pipe from the tank to the bowl and the flush tank valve tripper; of a disinfectant tank

mounted above the said tripper and located at one side of the flushing tank, a pipe connection that joins at one end to the disinfectant tank and which includes a laterally extended member that discharges into the flush tank flow pipe, a valve in the said pipe connection located directly under the flush

tank valve tripper, the latter including a pendent extension that forms a stem for the valve in the said pipe connection.
